TOBACCO STEMMER

Rupert E. Rundell, Rockville Centre, N. Y., assignor to American Machine & Foundry Company, a corporation of New Jersey

Application May 5, 1936, Serial No. 78,045

10 Claims. (Cl. 131—57)

This invention relates to an improvement in tobacco stemming machines of the type described in my Patent No. 1,992,773 dated Feb. 26, 1935 and more particularly to the stemming mechanism thereof, and is a substitute application for the application filed September 6, 1934, S. N. 742,989, by me, for a tobacco stemmer.

The main object of this invention is to provide stripping means which do not require to be in synchronism with the leaf carrying mechanism. Another object is to provide means for cutting the stripped stems at an even length and a device for adjusting said cutting means while the stemming machine is in operation. With these and other objects not specifically mentioned in view, the invention consists in certain constructions and combinations hereinafter fully described and then specifically set forth in the claims hereunto appended.

20 In the accompanying drawings which form a part of this specification and in which like characters of reference indicate the same or like parts:

Figs. 1 and 1a are sectional side elevations 25 which when joined at line A—A, represent a tobacco stemming machine provided with the improved stripping and cutting means;

Fig. 2 is a sectional end elevation of the improved stripping and cutting mechanism;

30 Fig. 3 is an end elevation showing the drive of the stripping and cutting mechanism and the adjusting device for the latter;

Fig. 4 is a sectional end elevation showing a modified form of the improved stripping mechanism;

Fig. 5 is a plan view of a portion of the adjusting device for the improved cutting mechanism;

Fig. 6 is a detail perspective view of the cutting knives in action;

Fig. 7 is a sectional end elevation showing the improved cutting mechanism provided with old type stripping blades which were used in former machines;

45 Fig. 8 is a sectional side elevation of Fig. 7;

Fig. 9 is a sectional end elevation showing a modified form of knife blades used in the improved cutting mechanism in combination with the old type stripping blades;

50 Fig. 10 shows the cutting action of the modified knife blades in a detail side view thereof; and

Fig. 11 is a detail plan view of the modified knife blades.

55 In carrying the invention into effect there is

provided a pair of rotary shafts each of which is provided with a set of supporting members fastened thereon, carded stripping bars movably mounted in said members in circumferentially spaced relation, means for rotating the shafts in opposite directions, mechanism for successively moving the carded stripping bars outwardly on their supporting members to strip a tobacco leaf drawn between said shafts and then retracting the bars in order to give a series of short, straight, interrupted motions for the purpose of producing closer stripping and less tearing of the leaves, and sets of relatively immovable knives on each shaft, each knife projecting outwardly between adjacent stripping bars to coact with a knife on the other shaft to sever at a predetermined length the stem of the leaf being stripped. In the best constructions contemplated there is provided means for adjusting the sets of knives axially on the shafts while the latter are in rotation, whereby the cutting range of the knives may be varied during the operation of the stemmer, and the cutting edges of the knives on the opposite shafts may be oppositely inclined and beveled or the cutters on one shaft 25 may have the form of female knife blades and the cutters on the other shaft may have the form of male knife blades. These various means and parts may be widely varied in construction within the scope of the claims for the particular device selected to illustrate the invention is but one of many possible concrete embodiments of the same. The invention, therefore, is not to be restricted to the specific construction shown and described.

35 In the operation of the improved tobacco stemming machine the tobacco leaves L to be stripped are placed by an operator on a continuously running conveyor belt 10 (Fig. 1a) with their butt ends overhanging the same. The latter is led over pulley 11 and a guide roller 12, and is driven continuously from the main drive of the machine. The butt ends of the leaves L are thus moved through a thresher or butt cleaning device T of conventional construction wherein the 40 stem butts are cleaned of laminae by a threshing operation in order that the stems S may be securely gripped later on by the gripping fingers of the conveyor chain which carries the leaves through the stemming mechanism.

50 While their butt ends are passing through the butt cleaning mechanism T the leaves L are held between conveyor belt 10 and a gripping belt 13, these two belts running in the same direction and at the same speed. Belt 13 is driven 55

and supported by means of pulleys 14 actuated from the threshing mechanism, which is driven by means of sprocket 15 and chain 16 from the main drive of the machine. Belt 13 is further-
5 more guided by means of rollers 17 pivoted to a bracket 18 attached to the housing of thresher T. In order to assure that leaves having stems of varying thickness will be held firmly between belts 10 and 13 while passing through the butt
10 cleaner T, belt 10 is equipped with a pair of ten-
sion rollers 19 pivoted to arms 20 which are spring mounted on studs 21.

After passing the butt cleaning mechanism T the butt ends of the leaves L are gripped be-
15 tween the opposed runs of twisted chain con-
veyors C and forwarded between gripper fingers G of an endless gripper chain, the grippers of
which are suitably actuated to seize each in-
dividual leaf at the cleaned butt end of the stem
20 S and carry the leaf between the rotary strip-
ping rolls where the remaining major portion of
the leaf is stripped from the stem. Further de-
scription of the twisted chain conveyor C is
deemed unnecessary as reference may be had to
25 my copending application cited above for a com-
plete disclosure of the same.

The improved stripping device (Figs. 1 and 2) consists of two stripping rolls each having a number of carded stripping bars 22 arranged in
30 cylindrical formation. Each bar 22 is equipped at its end with supporting studs 23 and 24 swing-
ably mounted in the cylindrical heads or sup-
porting members 25 and 26. The latter are
35 keyed to sleeve shafts 27 which are supported
in parallel relation in bearings of main frame
28. The described stripping rolls have parallel
axes and turn in opposite directions and work
in conjunction with one another (Fig. 2) upon
the leaves L drawn upwardly between them.

40 The position of the pins 29 of the stripping bars 22 during the stripping operation is con-
trolled by means of cam levers 30 attached to
the supporting studs 23 at one end of bars 22.
Each cam lever 30 carries a cam roller 31 en-
45 gaging in a cam track 32 of stationary cam 33
attached to main frame 28. The two stripping
rolls can be set so that upon engagement with
the leaf the two opposite bars 22 of the two rolls
follow each other as shown in Fig. 2 or mesh
50 with one another as illustrated in Fig. 4. The
advantage of using carded stripping bars ar-
ranged in cylindrical formation instead of cir-
cumferentially spaced blades provided with
notches forming a spiral stemway lies in the
55 elimination of the necessity of timing the strip-
ping rolls with the leaf conveyor means. To the
sleeve shaft 27 of each stripping roll is attached
a gear 34 each of which meshes with one of a
pair of intermeshing gears 35. Each gear 35 is
60 loosely mounted on a stud 36 held by main frame
28. This complete gear train is driven by means
of pinion 37 (Fig. 3) mounted on the main drive
shaft 38 of the machine.

In order to eliminate waste by making use of
65 that part of the stem which does not exceed the
thickness of the cross veins of the leaf, the strip-
ping device is equipped with an adjustable cut-
ting mechanism which cuts the stem S at the
desired point. The cutting mechanism consists
70 of a number of knife blades 39 attached to a
star wheel or spider 40 slidably supported on
each sleeve shaft 27, the cutting edge of the
knives on one shaft being inclined and beveled
in one direction and the cutting edge of the
75 knives on the other shaft being oppositely in-

clined and beveled. The star wheel 40 has as
many points as there are stripping bars 22 so
that each knife blade 39 is located between two
adjacent stripping bars 22 (Fig. 2). To each
star wheel 40 is attached a key 41 projecting 5
through a slot 42 of each sleeve shaft 27 into
an adjusting shaft 43 slidably supported in sleeve
shafts 27, thereby assuring simultaneous rota-
tion of the star wheels 40 and stripping bars
22. The cutting action takes place as two op-
posite knife blades 39, one of each stripping
roll, register with one another (Fig. 6).

The knife blades 39 may be adjusted axially
of the sleeve shafts 27 by turning one of the
knobs 44 (Fig. 3) mounted on a shaft 45 which 15
carries gear 46 engaging with rack sleeves 47
which are loosely mounted on each operating
shaft 43 of each stripping unit between a shoul-
der and a collar of the operating shaft (Fig. 1).
As the star wheel 40 of each unit is attached 20
by means of key 41 to an adjusting shaft 43,
flanges 40 can easily be moved axially on their
respective sleeve 27, thereby controlling the cut-
ting range of knife blades 39. This arrange-
ment of the cutting mechanism has the great 25
advantage of permitting the adjustment of the
cutting range while the machine is in opera-
tion and assuring that all stems will be cut at
an even and desired length. In order to fa-
cilitate the setting of the cutting range the 30
rack sleeve 47 is equipped with an indicator
finger 48 projecting through a slot in housing
50 and movable over a scale 49 attached to the
housing. The latter also supports shaft 45 and
is mounted on the main frame 28 of the ma- 35
chine.

Referring now to Figs. 7 and 8, the just de-
scribed adjustable cutting mechanism can also
be used in combination with stripping blades
of the old type used in my prior Patent No. 40
1,968,098, granted July 31, 1934.

Referring to Figs. 9, 10, and 11, the sets of
straight knife blades 39 are replaced by a pair
of male knife blades 51 and a pair of female
knife blades 52, mounted on flanges 53 keyed 45
to each of the adjusting shafts 43. The cutting
action takes place as two opposite male and
female knife blades 51 and 52 register with
one another (Fig. 10).

What is claimed is:

1. In a tobacco stemmer, the combination with
a pair of rotary sleeve shafts, each of said sleeve
shafts being provided with a set of supporting
members fastened thereon, of carded stripping
bars movably mounted in said members in cir-
cumferentially spaced relation, means for rotat-
ing said sleeve shafts in opposite directions,
mechanism for successively moving the carded
stripping bars outwardly on their supporting
members to strip a tobacco leaf, drawn between
said sleeve shafts and then retracting said bars,
sets of knives splined on each of said sleeve
shafts, each knife projecting outwardly between
adjacent stripping bars to coact with a knife on
the other sleeve shaft to sever at a predetermined
length the stem of the leaf being stripped, and
means for adjusting the sets of knives axially on
their sleeve shafts while the latter are in ro-
tation, whereby the cutting range of the knives
may be varied during the operation of the 70
stemmer.

2. In a tobacco stemmer, the combination with
a pair of rotary sleeve shafts, each of said sleeve
shafts being provided with a set of supporting
members fastened thereon, of carded stripping 75

- bars movably mounted in said members in circumferentially spaced relation, means for rotating said sleeve shafts in opposite directions, mechanism for successively moving the carded 5 stripping bars outwardly on their supporting members to strip a tobacco leaf, drawing between said sleeve shafts and then retracting said bars, sets of knives splined on each of said sleeve shafts, each knife projecting outwardly between 10 adjacent stripping bars to coact with a knife on the other sleeve shaft to sever at a predetermined length the stem of the leaf being stripped, and means for adjusting the sets of knives axially on their sleeve shafts while the latter are in rotation, whereby the cutting range of the knives 15 may be varied during the operation of the stemmer, the cutters on one shaft having the form of female knife blades and the cutters on the other shaft having the form of male knife blades.
6. In a tobacco stemmer, the combination with 10 a pair of rotary shafts, of stripping means, mechanism carried by each of said shafts for supporting said stripping means, means for rotating said shafts in opposite directions to strip a tobacco leaf located between them, devices for 15 drawing leaves between said shafts, a knife carried by each of said shafts, one positioned to coact with the knife on the other shaft to sever the stem of the leaf at a predetermined point during its travel between said shafts, and means 20 mounting at least one of said knives for adjustment along its shaft to vary the cutting position said mounting means including knife carrying elements separate from said supporting mechanism in direct sliding engagement with said 25 shaft for adjusting the knife therealong independently of said stripping means.
7. In a tobacco stemmer, the combination with 30 a pair of rotary shafts, of stripping means carried by each of said shafts, means for rotating said shafts in opposite directions to strip a tobacco leaf located between them, devices for 35 drawing leaves between said shafts, a knife carried by each of said shafts, one positioned to coact with the knife on the other shaft to sever the stem of the leaf at a predetermined point during its travel between said shafts, and means for adjusting said knives longitudinally of said shafts 40 during the operation of the stemmer.
8. In a tobacco stemmer, the combination with 40 a pair of rotary shafts, of stripping means carried by each of said shafts, means for rotating said shafts in opposite directions to strip a tobacco leaf located between them, devices for 45 drawing leaves between said shafts, a knife carried by each of said shafts, one positioned to coact with the knife on the other shaft to sever the stem of the leaf at a predetermined point during its travel between said shafts, and interconnected means for simultaneously and equally 50 adjusting the knives on both shafts.
9. In a tobacco stemmer, the combination with 55 a pair of rotary shafts, of stripping means carried by each of said shafts, means for rotating said shafts in opposite directions to strip a tobacco leaf located between them, devices for 60 drawing leaves between said shafts, and a knife on each of said shafts, one positioned to coact with the knife on the other shaft to sever the stem of the leaf at a predetermined point during its travel between said shafts, and means for 65 adjusting at least one of said knives on said shaft during the operation of the stemmer, comprising a member extending along said shafts from an intermediate portion thereof to beyond the stripping means, and movable parallel to the length of said shafts, and connections between said member and said knife permitting rotation of the knife on said shaft relative to the member, for moving the knife longitudinally 70 of the shaft on movement of said member.
10. In a stemming machine, the combination with 70 a pair of approximately parallel rotating stemming rolls each provided with stripping 75

means coacting to stem leaves between said rolls, of gripper means travelling diagonally relative to the axis of said blades to draw leaves through and along said rolls, coacting knives on said rolls adjustable to cut the stems at any desired point during their diagonal travel through the rolls, and means for adjusting and supporting

said knives comprising spiders surrounding the axes of said rolls, a series of knives on said spiders with the knives on one spider arranged for shearing action relative to those on the other, and means for adjusting said spiders axially of the rolls and relative to said stripping means.

RUPERT E. RUNDELL.
